US00D674528S

(12) **United States Design Patent**
Paz

(10) **Patent No.:** **US D674,528 S**
(45) **Date of Patent:** **** Jan. 15, 2013**

(54) **LED MODULE**

(75) Inventor: **Francisco Gomez Paz**, Milan (IT)

(73) Assignee: **Luceplan SpA**, Milan (IT)

(**) Term: **14 Years**

(21) Appl. No.: **29/403,277**

(22) Filed: **Oct. 4, 2011**

(30) **Foreign Application Priority Data**

Apr. 5, 2011 (EM) 001846007-0006

(51) **LOC (9) Cl.** **26-05**

(52) **U.S. Cl.** **D26/72**

(58) **Field of Classification Search** D26/72,

D26/73, 80, 88, 91, 128, 131; 362/147, 404-408,
362/431, 432

See application file for complete search history.
